UNITED STATES PATENT OFFICE.

CHRISTIAN WERTHNER, OF TORONTO, CANADA, ASSIGNOR TO THE GEN-
DRON MANUFACTURING COMPANY, LIMITED, OF TORONTO, CANADA.

KNOCKDOWN WICKER CHAIR.

SPECIFICATION forming part of Letters Patent No. 691,216, dated January 14, 1902.

Application filed October 15, 1900. Serial No. 33,156. (No model.)

To all whom it may concern:

Be it known that I, CHRISTIAN WERTHNER, foreman, of the city of Toronto, in the county of York, Province of Ontario, Canada, have 5 invented certain new and useful Improvements in Knockdown Wicker Chairs, of which the following is a specification.

The object of my invention is to devise a wicker chair which may be knocked down for shipment; and it consists, essentially, in the details of construction hereinafter more specifically described and then definitely claimed.

Figure 1 is a perspective view of my wicker chair set up. Fig. 2 is a similar view of the 15 same knocked down.

In the drawings like letters of reference indicate corresponding parts in the different figures.

The chair is made in five parts—namely, 20 two side sections A, a back panel B, a seat C, and cross-braces D. Each side section comprises a front standard E and a rear standard F, suitably connected by cross-braces and ornamental wicker-work. In chairs as ordinary 25 narily constructed the rear standards form part of the back; but this construction is not feasible in a knockdown chair. The seat comprises two or more cross-bars G, suitably connected with wicker-work or in any other 30 suitable manner. The back panel comprises the back proper, H, formed of ornamental wicker-work, and a supporting-frame comprising two or more cross-bars I, connected together by suitable connecting-pieces, such 35 as J.

The cross-braces D may be of any suitable construction for the purpose of connecting the standards of the chair below the seat.

The standards E and F have holes a formed 40 in their inner sides, which are adapted to receive the suitably-shaped ends of the cross-pieces G of the seat, cross-bars I of the back, and the ends of the cross-braces D. When the chair is finally set up for use, the ends of 45 the cross-bars are secured in the holes a by gluing or nailing, as desired. The lower ends of the standards may be formed with ordinary feet or secured to rockers K, as shown, the rockers being provided with suitable holes 50 to receive the lower ends of the standards.

From the construction described it appears

that all the connections between the parts of the chair are substantially parallel to one another, so that the chair is readily taken apart by pulling off one of the side sections 55 and then by removing the back and seat, the direction of motion in separation being the same in each case.

The elements of the construction which are most important in making my knockdown 60 chair are the combination, with the side sections, of the standards of the chair and the formation of the back upon a frame which is detachably connected to the inner sides of the rear standards.

With a chair constructed as described I am able to ship the goods knocked down, so that twenty may be packed in a space which formerly accommodated only four. This is a point of great advantage both to the manufacturer and buyer, particularly where freight 70 has to be paid for according to the amount of space occupied.

I claim nothing in the special arrangement of the wicker-work on the chair, as the pattern and construction of this portion of the 75 chair can be widely varied, the underlying principle being the same in every case.

What I claim as my invention is—

1. In a knockdown wicker chair, side sections comprising front and rear standards suitably connected and having holes upon their inner faces to receive the ends of cross-bars on the seat and back sections, combined with an unframed seat comprising front and 85 rear cross-bars suitably connected, and a back panel and an independent supporting-frame for said back panel comprising cross-bars, the cross-bars of the seat and back sections being extended and detachably engaged in the holes 90 in the adjacent faces of the standards of the side sections, substantially as shown and described.

2. In a chair, side sections comprising front and rear standards suitably connected, in 95 combination with an unframed seat comprising front and rear cross-bars suitably connected; cross-braces below the seat; and a back panel and an independent supporting-frame therefor comprising cross-bars suitably connected, the standards of the side sections having holes formed therein to detachably re-

ceive the ends of the cross-bars of the seat, the cross-braces and the cross-bars of the supporting-frame of the back panel, substantially as and for the purpose specified.

- 5 3. In a chair, side sections comprising front and rear standards suitably connected; and a seat detachably connected to the side sections in combination with a back panel comprising the wicker back proper and a supporting-frame comprising cross-bars and suitable connections, the rear standards of the side sections having holes formed therein to receive the ends of the cross-bars of the frame of the back panel, substantially as and for
10 15 the purpose specified.
4. In a chair, side sections comprising front and rear standards suitably connected, in

combination with a seat comprising front and rear cross-bars suitably connected; and a back panel, an independent supporting-frame upon which said panel is supported, said frame comprising cross-bars suitably connected, the standards of the side sections having holes formed therein to receive the ends of the cross-bars of the seat and cross-bars of said supporting-frame of the back panels by mortise-and-tenon connections, substantially as and for the purpose specified.

Toronto, September 24, 1900.

CHRISTIAN WERTHNER.
